No. 36,678.

Patented December 15, 1903.

UNITED STATES PATENT OFFICE.

HELGE A. HAUGAN, OF CHICAGO, ILLINOIS.

DESIGN FOR A SAVINGS-BANK.

SPECIFICATION forming part of Design No. 36,678, dated December 15, 1903.

Application filed November 10, 1902. Serial No. 130,816. Term of patent 7 years.

To all whom it may concern:

Be it known that I, HELGE A. HAUGAN, a citizen of the United States, residing at Chicago, Illinois, have invented a new, original, and ornamental Design for a Savings-Bank, which is shown in the accompanying drawing, the same being a perspective view of a savings-bank having my design embodied therein.

I claim—
The ornamental design for a savings-bank, as shown.

HELGE A. HAUGAN.
